OTHER PUBLICATIONS

Atlas Copco "RT Series Hydraulic Torque Wrench" datasheet dated Jun. 2015.

Primary Examiner — Austin Murphy

(74) *Attorney, Agent, or Firm* — Knobbe, Martens, Olson & Bear, LLP

(57) **CLAIM**

The ornamental design for a hydraulic torque wrench as shown and described.

DESCRIPTION

The patent or application file contains at least one drawing executed in color. Copies of this patent or patent application publication with color drawing(s) will be provided by the Office upon request and payment of the necessary fee.

1.1: Perspective

1.2: Perspective

1.3: Top

1.4: Right

1.5: Front

1.6: Left

1.7: Back

1.8: Bottom

The design resides in the shape, color and configuration of the article as shown; no protection is sought for the matter shown in ghost lines and unshaded.
